ABSTRACT OF THE DISCLOSURE

Methods for the conversion of D-glucose to D-fructose are disclosed. Enzymes derived from *Aerobacter levanicum* are used. A glucose isomerizing enzyme is produced when *Aerobacter levanicum* is grown on a substrate containing xylose, preferably unpurified birchwood sulfite liquor.

BACKGROUND OF THE INVENTION

The commercial production of fructose from glucose is desirable because of increased sweetness of the resulting product over pure glucose. The fully converted product is a syrup that resembles invert sugar, i.e. it is about 50% fructose and 50% glucose.

The conversion of glucose to fructose can be catalyzed in general by bases, such as sodium hydroxide, but the conditions are such that undesirable side products may result. Reports abound in the literature, both general and patent, concerning enzymes derived from microbiological sources which catalyze the conversion of glucose to fructose with a minimum of side reactions. All of the commercially feasible enzyme sources in the past have been derived from fermentations of various strains of *Streptomyces* in a medium in which xylose or xylan is used to induce the enzyme. A major disadvantage of such derived enzymes is the necessity for a portion of the carbon source of the fermentation medium to be composed of purified xylose. We have devised a method that employs, without any purification, hardwood sulfite liquors (particularly birchwood sulfite liquor), a readily available waste product of pulp and paper mills, as the source of xylose. The microorganism *Aerobacter levanicum* is suitable for this purpose. Cells of *Aerobacter levanicum* contain high amounts of glucose isomerizing activity when grown on a source of xylose.

The assay of the glucose isomerizing activity of enzyme extracts is carried out in 1 M glucose, 3×10^{-4} M CoCl_2 , 3×10^{-3} M MgSO_4 , 0.035 M phosphate buffer at pH 7.5 and 55° C. The initial rate of enzymatic conversion of glucose to fructose is determined by measuring the rate of fructose formation by the HCl-skatole method, as described by Pogell in *J. Biol. Chem.* 211:143, 1954. One unit of activity corresponds to a rate of $1 \mu\text{M}/\text{min}$. of fructose formed under the above conditions. The activity of glucose isomerase obtained from simultaneous cell propagation and enzyme induction is measured by using intact cells as enzyme instead of using a cell-free extract.

SUMMARY OF THE INVENTION

The invention comprises a method of isomerizing glucose to fructose using enzymes derived from the microorganism, *Aerobacter levanicum*, grown on a suitable substrate containing xylose, a nitrogen source, and Co^{++} .

2

DETAILED DESCRIPTION

The microorganism used in this process is *Aerobacter levanicum* obtained from the Northern Regional Research Laboratory of the United States Department of Agriculture at Peoria, Ill., and identified as deposit NRRL B-1678.

The *A. levanicum* organism can be grown on a medium containing carbon and nitrogen. In order to produce converting enzyme, however, xylose must be present in the substrate.

For isomerization to take place, Co^{++} must be present in the isomerizing medium or the cells or enzyme must have been grown on a substrate containing Co^{++} . For best results K^+ or Mg^{++} also are present, either during cell growth or in the isomerizing medium.

As previously mentioned, hardwood sulfite liquor, specifically birchwood sulfite liquid is a suitable source of xylose. The birchwood sulfite liquor (B.S.L.) is not purified or sterilized as is required in the growth of other microorganisms which produce glucose isomerase. This is an important commercial consideration as this syrup (the isomerized glucose-fructose syrup) is intended to replace conventional invert sugar in certain syrups, candy and baking applications, and thus must be competitive in price.

In producing the enzyme, the *A. levanicum* cells can be propagated on a suitable growth medium and then added to a xylose medium (B.S.L.) to induce enzyme or the growth medium can contain xylose so that enzyme is induced as the cells are grown.

The enzyme can be added to the glucose substrate in the form of air dried cells or the enzyme can be separated from the cells by sonification and only the enzyme added to the glucose substrate. Examples of both of these processes are given hereinafter.

A suitable medium for producing *A. levanicum* cells contains yeast extract or corn steep liquor as nitrogen sources and D-xylose and D-glucose as carbon sources. Total solids content is 2% to 4% w/v. of medium. The medium is inoculated with 1% to 5% *A. levanicum* cells. The cells are incubated for 12 to 24 hours at a temperature of 24 to 30° C. in shake flask culture in a Gyrotory shaker with a speed of 150 r.p.m. to 300 r.p.m., at a pH value of 7-8. This produces $2.5-4.0 \times 10^9$ cells per ml. of medium.

A suitable medium for producing enzyme contains corn steep liquor or yeast extract as nitrogen sources and birchwood sulfite liquor and glucose as carbon sources, with a solids content of 5 to 10%. This is inoculated with 1 to 2% *A. levanicum* cells v/v. of medium. This is fermented for 18 to 24 hours at a pH value of 6 to 8 and a temperature of 24 to 30° C. in a Gyrotory shaker at a speed of 150 r.p.m. to 300 r.p.m. This produces enzyme of 0.5 to 1.0 units of activity per ml. of medium.

The cells can be dried for 24 to 72 hours at a temperature of 20 to 30° C., to a moisture content of 5 to 10%.

The cells can be sonified (ultrasonic fragmentation) to solubilize the enzyme at a force of 100 to 300 watts for 3 to 15 minutes depending upon the amount to solubilize.

The foregoing are the criteria established when cell growth and enzyme induction are not carried out simultaneously. Following are criteria for simultaneous cell propagation and enzyme induction.

A suitable medium is yeast extract, corn steep liquor or yeast extract plus Bactopeptone, and D-xylose with a solids content of 2 to 4%. An inoculation of *A. levanicum* of 1 to 2% v/v. is added to the medium. The micro-

organism is incubated for 24 to 40 hours at a temperature of 24 to 30° C. and a pH of 5.5 to 9.0, in a Gyrotory shaker at a speed of 100 r.p.m. to 300 r.m.p. This produces enzyme of potency of 0.3 to 0.4 units per ml. of medium. These cells and enzymes can be dried or the enzymes separated as previously described.

Enzyme or cell-enzyme mixtures from any of the proceeding fermentations may be used to isomerize glucose to fructose according to the following criteria.

If air dried cells are used, from about 0.5% to about 1% w./v. of cells are added to a glucose syrup of 36 to 50% glucose having a D.E. (Dextrose Equivalent) of 89 to 98 and a solids content of 40 to 60%. The glucose syrup contains 0.1 to 0.6 μ M Co^{++} , 1 to 6 μ M Mg^{++} , and 10-40 μ M phosphate. The pH is controlled between about 6.5 and about 7.5 and the temperature is maintained between about 50° C. and about 60° C. The conversion is allowed to proceed for about 24 to 72 hours.

The resultant product has 47 to 52% dextrose and 40 to 52% fructose. This syrup is treated by centrifugation to remove the cells followed by activated carbon treatment and ion exchange to produce a commercial product of the following composition: 40-52% fructose, 47 to 52% glucose, 2 to 8% oligosaccharides, all on a dry substance basis.

Following are specific examples of the processes of this invention.

EXAMPLE NO. I

The process is carried out in a 250 ml. Erlenmeyer flask containing 100 ml. of a suitable growth medium. The flask is shaken by a rotary shaker (200 revolutions/minute with a 1 inch orbit) at a temperature of 23° C. for 24 hours. The flask is inoculated from a YM broth (pH 7.0) with *Aerobacter levanicum* NRRL B-1678. Two percent v./v. of *A. levanicum* is added to the flask. The composition of the growth medium is the following:

	Percent
Yeast extract	2.0
Glucose	0.2
Xylose	0.8
$\text{CoSO}_4 \cdot 7\text{H}_2\text{O}$	0.009
KCl	0.18
Tap water	96.8

The pH is adjusted to 7.5 with a 50% KOH solution and the flask containing the medium is sterilized for 10 minutes at 121° C. in an autoclave before being inoculated with *A. levanicum*. After 24 hours the fermentation is stopped and the cells are harvested. 7.3 mg. cells/ml. growth medium are recovered and the enzyme recovered has 0.3 units/ml. activity based on the quantity of growth medium.

EXAMPLE NO. II

The process is carried out in thirty 1 liter Erlenmeyer flasks in a two-stage process. The first stage is a growth process in which 300 ml. of medium is incubated at 22°-25° C. for 16 hours on a rotary shaker with a 2 inch orbit at 175 r.p.m. The flasks are each inoculated with 3 ml. of cultured *Aerobacter levanicum*. The composition of the growth medium is the following:

	Percent
Yeast extract	2.0
Glucose	0.5
Tap water	97.5

The pH is adjusted to 7.5 with a 50% KOH solution and the flasks containing the medium are sterilized for 15 minutes at 121° C. in an autoclave before adding the *A. levanicum*.

The second stage of the process is an induction phase in which the desired glucose isomerase enzyme is produced in response to the introduction of xylose into the fermentation. A cheap source of xylose is the hardwood sulfite

liquors from pulp and paper mills. The particular source used in this example is a birchwood sulfite liquor concentrated to between 50 and 57 percent solids. The medium prepared with the birchwood sulfite liquor is introduced into the fermentation process by adding 300 ml. of nutrient medium to each of the flasks and incubating an additional 24 hours at 22-25° C. with the shaking speed increased to 225 r.p.m. The composition of the added medium is the following:

	Percent
Birchwood sulfite liquor (as xylose)	4
$\text{CoSO}_4 \cdot 7\text{H}_2\text{O}$	0.0036
KCl	0.024
Tap Water	95.9724
The PH is adjusted to 7.5 with 50% KOH.	

The cells are harvested and washed by centrifugation and the resulting cell paste, 240 g., from 18 liters of total medium (both stages), may be sonified to solubilize the enzyme, or the cells may be spread out and allowed to air dry at room temperature. In either procedure, the yield of enzyme is 0.97 units per ml. of culture medium.

EXAMPLE NO. III

One gram of air dried cells having an activity of 480 units/g. are added to 100 ml. of 36% w./v. glucose solution containing in addition 6×10^{-4} M CoCl_2 and 6×10^{-3} M MgSO_4 . The syrup conversion is allowed to continue for 72 hours at 55° C. with the pH controlled automatically at 6.8 by the addition of 1 N NaOH. The conversion is stopped by centrifugation. The syrup is purified by activated carbon treatment, ion exchanged and concentrated. The resultant product has the following composition: 40% w./v. solids with 50.3% fructose and 49.7% glucose.

The identity of the conversion products as well as the percent composition of the syrups of the foregoing examples is confirmed by both paper and thin layer chromatography and by gas chromatography of the silyl derivative by known methods as described in *Journal of The Association of Official Agricultural Chemists*, 1198-1201, 53 (b), 1970.

We claim:

1. A two-stage method of preparing an enzyme with substantial glucose isomerizing activity from *Aerobacter levanicum* comprising the steps of:

(a) combining in a first stage-culture medium, the microorganism, *Aerobacter levanicum*, and sources of nitrogen and carbon for a period of about 12 to about 24 hours, during which time predominately growth of the microorganism takes place, and

(b) in the second stage adding cobalt and unpurified hardwood sulfite liquor to the said culture medium to induce the production of glucose isomerizing enzyme, and

(c) thereafter recovering said glucose isomerizing enzyme.

2. The method of claim 1 wherein the medium contains a magnesium salt.

3. The method of claim 2 wherein the yield of enzyme is at least about 0.9 units per ml. of medium.

4. A method of converting glucose to fructose comprising treating an aqueous solution containing glucose with a glucose isomerizing enzyme derived from the microorganism *Aerobacter levanicum* as produced by the process of claim 1, maintaining the glucose isomerizing enzyme in contact with the glucose containing aqueous solution under glucose isomerizing conditions, and converting at least 40% of the glucose to fructose.

5. The method of claim 4 wherein the glucose solution contains 35 to 55% solids in an aqueous solution of D.E. 90 to 98.

6. The method of claim 4 wherein the conversion is at a temperature of 50 to 65° C., a pH of 6.0 to 7.5, and

an enzyme concentration of 1.0 units/ml. to 5.0 units/ml. for 24 to 72 hours.

7. The method of claim 6 wherein the conversion is carried out with 0.5 to 1% w/v. dried cells as the enzyme source.

8. The method of claim 4 including the step of recovering a converted glucose solution having a composition of 47 to 52% glucose, 40 to 52% fructose and 2 to 8% oligosaccharides on a dry substance basis.
